UNITED STATES PATENT OFFICE.

ARTHUR GOHMANN, OF STETTIN, GERMANY, ASSIGNOR TO STETTINER CHAMOTTE-FABRIK ACTIEN-GESELLSCHAFT VORMALS DIDIER, OF STETTIN, GERMANY, A CORPORATION OF GERMANY.

CHAMBER-OVEN.

1,079,003.

Specification of Letters Patent. Patented Nov. 18, 1913.

Application filed August 30, 1912. Serial No. 717,832.

To all whom it may concern:

Be it known that I, ARTHUR GOHMANN, a subject of the German Emperor, and a resident of Stettin, Germany, have invented certain new and useful Improvements in Chamber-Ovens, of which the following is a specification.

My present invention has for its object to provide an improved arrangement of heating flues and their connections in a chamber oven such as are used in the manufacture of coke, for the purpose of securing a very uniform heating effect. The invention has been devised particularly for use in chamber ovens having upright chambers tapering from the bottom toward the top, and horizontal or longitudinal heating flues through which the combustion products pass constantly in the same direction. In chamber ovens of this type, the superposed heating flues have sometimes been connected in pairs, the two flues of each pair communicating at one end by means of a duct; the lower flue of each pair was connected with means for supplying fuel (gas) and air thereto at the other end, while the upper flue of each pair was connected, at the end distant from the connecting duct, with a channel or flue for carrying away the off-gases. In this construction, therefore, fresh fuel is supplied to the lower flue of each pair, whereas the upper flue of each pair will receive the off-gases or combustion products from the companion lower flue. If such an oven is operated with the combustion gases flowing constantly in the same direction (that is to say, without periodical reversal), the coking operation will proceed unevenly, especially in the lower portions of the coking chambers, and the operation of the oven will therefore not be economical.

When my present invention is applied to a chamber oven of the above-indicated type, the defect just referred to is avoided by arranging the heating flues in at least two superposed groups or sets, the flues of the upper group being connected at one end with off-gas flues or waste flues, and the flues of the other (lower) group being connected at the corresponding end, with ducts for supplying air and fuel (gas); at their other ends, all the heating flues of both groups are connected by a common conveying channel in such a manner that fresh fuel and air will

pass constantly in the same direction through the flues of the lower group, while the off-gases or combustion products from the said lower group of flues will flow constantly in the same direction through the flues of the upper group. With this improved arrangement, a very thorough utilization of the heat of the combustion gases is obtained, the lower portions of the coking chambers being heated more strongly than their upper portions, in accordance with the upward tapering of said chambers, so as to secure a uniform conversion of coal into coke and an economical operation of the oven. In order to facilitate an accurate regulation of the heating effect, I prefer to provide a third group of heating flues between the two groups mentioned above, so that the structure will comprise a lower group of heating flues connected at one end with ducts for supplying air and fuel, an upper group of flues connected at one end with off-gas flues, and an intermediate group of flues connected at one end alternately (according to the position of valves or other controllers) with off-gas ducts or with ducts for supplying fuel and air, while the other ends of the flues of this intermediate group are connected with the above-mentioned common conveying channel in such a manner that either fresh fuel or off-gases may be caused to pass through the heating flues of the intermediate group.

A typical example of a chamber oven embodying my invention is shown in the accompanying drawings, in which—

Figure 1 is a vertical section through such an oven, taken on the line A—B of Fig. 2; Fig. 2 is a horizontal section, the upper portion of Fig. 2 being taken on the line C—D of Fig. 1, the central portion on the line E—F of Fig. 1, and the lower portion on the line G—H of Fig. 1; and Fig. 3 is a vertical section, the left-hand portion of Fig. 3 being taken on line J—K of Fig. 1, the central portion on line L—M of Fig. 1, 100 and the right-hand portion on the line N—O of Fig. 1.

The chamber oven shown in the drawings is provided with upright gasifying or coking chambers 1 (Figs. 1 and 3) of a cross-section decreasing upwardly. In the heating walls or partitions 2 which separate adjacent oven chambers, I provide, for each

half of the oven, three groups of superposed horizontal or longitudinal heating flues 3, 4, and 5 respectively. When viewed in cross-section (Fig. 3), each heating wall has two series or sets of heating flues, each of these sets lying adjacent to one of the longer sides of one of the coking chambers separated by said wall or partition. The heating flues of one oven-half are separated from those of the other half by vertical partitions 6 disposed at the center of the oven. The heating flues of each half are not continued to the partitions 6, but gaps are left at the inner ends of the flues, thus forming conveying channels 7 at each side of the partitions 6, to connect the inner ends of all the heating flues which are on the same side of the partition 6 and belong to the same set or series.

In the side walls 8 of the oven, adjacent to the shorter sides of the coking chambers 1, I provide air-distributing ducts 9 (Fig. 2) and off-gas ducts 10, regulatable by means of suitable controllers, such as the slides 11 and 12 respectively. The air-distributing ducts 9 are connected with the outer ends of the heating flues 3 and 4 of the lower group and of the intermediate group respectively, by means of short branch ducts 13 which may be regulated or even shut off by slides 14 or other appropriate devices. The off-gas ducts 10 are connected with the outer ends of the heating flues 4 and 5 of the intermediate group and of the upper group respectively, by means of short branch ducts 15 controlled by slides 16. In addition to this, the heating flues 3 and 4 of the lower and of the intermediate group respectively are connected at their outer ends with fuel-supply ducts 17 containing shut-off valves or cocks 18 and connected in pairs with fuel-supply pipes (gas pipes) 20 each provided with a shut-off valve 19. The pipes 20 are vertical and are connected, at the respective ends of the oven, with horizontal fuel mains or gas mains 21.

The air-distributing ducts 9 and the off-gas ducts 10 of each oven-half are connected with chambers or collectors 22 and 23 respectively, and each of these chambers, by the operation of reversing slides 24 closing the channels 25 and 26 alternately, is placed in communication with the regenerators 27 and 28 respectively in such a manner as to cause the air for supporting combustion to pass constantly in the same direction through the chambers 22 and the ducts 9, while the off-gases pass constantly in the same direction through the ducts 10 and the chambers 23.

The slides 14 and 16 may be accessible for operation from the outside through suitable channels normally closed by plugs, such arrangement being well-known and therefore not shown in the drawings.

The operation of the above-described oven is as follows: In the position illustrated by Fig. 1, all the slides 14 controlling the branch air-ducts 13 are open, the slides 16 controlling the branch off-gas ducts 15 of the upper group 5 of heating flues are also open, but the slides 16 controlling the branch off-gas ducts 15 of the intermediate group 4 of heating flues are closed, while the cocks or valves 18 of all the fuel-supply ducts 17 are open. The air for supporting combustion enters one of the regenerators 27, 28 in the usual way, and is preheated therein. The air passes constantly in the same direction through the ducts 9 and thus reaches the outer ends of the heating flues 3 and 4 of the lower and the intermediate group. Gas is supplied to the same outer ends through the ducts 17, and combustion takes place in said heating flues. The fresh combustion gases travel through the heating flues 3 and 4 from their outer ends to the center of the oven, where they rise in the conveying channels of the respective partitions 2. From the channels 7 the combustion products or off-gases pass into the heating flues of the upper group 5 and travel from their inner ends to their outer ends, finally reaching the branch ducts 15 and passing through the off-gas ducts or flues 10 to one of the chambers 23 and thence through one of the regenerators 27, 28, heating it in the well-known manner. It will therefore be understood that fresh combustion gases pass through the heating flues of the lower group 3 and of the intermediate group 4, while off-gases travel through the heating flues 5 of the upper group. The lower and the intermediate portions of the coking chambers 1 are therefore subjected to a relatively strong heat, as is desirable in view of the relatively large cross-section of these portions of the oven, while the upper portions of the oven, which have a smaller cross-section, are heated less strongly. The heating effect may be regulated in a manner corresponding to the upwardly tapering form of the coking chambers 1, by opening the individual gas valves 18 more or less, and by adjusting the slides 14 and 16 so as to regulate on the one hand, the effective cross-section of the branch air-ducts 13 leading to the heating flues 3 and 4 of the lower group and of the intermediate group respectively, and on the other hand, the effective cross-section of the branch off-gas ducts leading from the heating flues 5 of the upper group. Another mode of regulation, which may be used in conjunction with the one described above, consists in supplying off-gases instead of fresh fuel, to all or part of the heating flues 4 of the middle or intermediate group, in the same manner in which the flues 5 of the upper group are

fed with off-gases. If it be desired to supply off-gases to all of the heating flues 4 of the intermediate group, the valves 18 of the corresponding gas-supply ducts 17 are closed, as well as the slides 14 of the respective branch air-ducts 13, the slides 16 of the corresponding branch off-gas ducts 15 being opened at the same time. In this case fresh gases will pass only through the heating flues 3 of the lower group, from the outer ends of said flues toward the center of the oven, then rising in the conveying channels 7, the combustion products or off-gases then traveling through the heating flues 4 and 5 of the intermediate and upper groups of flues respectively, and finally leaving through the branch off-gas ducts 15 and the ducts 10. By properly adjusting the slides 16 of the branch off-gas ducts 15 belonging to the heating flues 4 of the intermediate group, the heating effect may be regulated as required. A further regulation of the heating effect may be obtained by supplying fresh gases to the 25 lower flues of the intermediate group 4 and off-gases to the upper flues of said intermediate group. The improved arrangement described above therefore enables me to regulate the heating effect very accurately, in accordance with the upwardly diminishing cross-section of the coking chambers 1.

In order to secure a uniform coking of the mass of coal contained in the chambers 1, in view of the upwardly diminishing cross-section of said mass or body, the amount of heat supplied should be greatest at the level or region of the lowermost heating flues, and least at the level or region of the uppermost heating flues, a proper gradation of the heating effect being observed for the intermediate flues. The combustion gases escaping from the heating flues at the lower portions of the heating walls or partitions 2 cannot, however, be utilized for heating these portions of the chambers 1, for the reason that their temperature is too low. Therefore, in the case of the oven construction referred to as old at the beginning of this specification, in which construction the superposed heating flues are connected only in pairs, (the off-gases of each lower heating flue escaping directly through the upper flue of the same pair), the heating effect 50 will not be uniform, and consequently the conversion of coal into coke will proceed unevenly.

With my improved arrangement of heating flues, the combustion gases can be utilized economically for heating the oven, without impairing the uniformity of the coking process, for the reason that with the new arrangement the combustion gases emanating from a group of heating flues located 55 at the lower portion of the oven, are led to

a group of heating flues located at the upper portion of the oven. The stronger heating required for the lower portion of the oven is thus secured by employing fresh gases at this lower portion, and the less energetic heating required by the upper portions of the coking chambers is obtained by using the off-gases for heating this portion. 70

The herein described invention enables me to obtain a uniform conversion of the coal into coke throughout the entire coking chambers, in a very short time and with a very economical utilization of the heat contained in the combustion gases, thus increasing the efficiency of the oven. 75

The arrangement of heating flues described above may also be applied to chamber ovens having recuperators in which the air for supporting combustion is heated by the off-gases through heat-transferring 80 walls.

Various modifications may be made without departing from the nature of my invention as set forth in the appended claims.

I claim as my invention:

1. A chamber oven having upright, upwardly tapering gasifying chambers and heating walls for said chambers, said walls containing longitudinal heating flues arranged in groups at different levels, a conveying channel connecting like ends of all the flues of said groups, ducts for supplying fuel and air to the other ends of a lower group of flues, and off-gas ducts connected with the flues of an upper group at the ends 100 distant from said conveying channel, whereby fresh gases will be caused to pass constantly in the same direction through the heating flues of the lower group, while the off-gases from the flues of the lower group 105 will be caused to travel constantly in the same direction through the flues of the upper group, thus securing a thorough utilization of the combustion gases and a heating effect which in accordance with the upwardly diminishing cross-section of the 110 gasifying chambers is greater at the lower portions of said chambers than at their upper portions, for the purpose of obtaining an even gasification or coking process. 115

2. A chamber oven having upright, upwardly tapering gasifying chambers and heating walls for said chambers, said walls containing longitudinal heating flues arranged in three groups at different levels, a conveying channel connecting like ends of all the flues of said three groups, ducts for supplying fuel and air to the other ends of the flues of the lower and the intermediate groups of flues, off-gas ducts connected with the flues of the intermediate and upper groups at the ends distant from the said conveying channel, and devices for controlling the alternate connection of the intermediate group of flues with the off-gas ducts 120 125 130

or with the air and fuel supply ducts respectively, whereby the flues of the intermediate group may receive either fresh gases, or off-gases from the lower group of flues.

3. A chamber oven having gasifying chambers and heating walls for said chambers, said walls containing longitudinal heating flues arranged in groups, a conveying channel connecting the like ends of all of said flues, ducts for supplying fuel and air to the other ends of a lower group of flues, and off-gas ducts connected with the flues of an upper group at the ends distant from said conveying channel.

4. An oven having gasifying chambers and heating walls for said chambers, said walls containing longitudinal heating flues arranged in three groups at different levels, a conveying channel connecting like ends of the flues of said three groups, ducts for supplying fuel and air to the other ends of the flues of the lower and the intermediate groups, off-gas ducts connected with the flues of the intermediate and upper groups at the ends distant from the said conveying channel, and devices for controlling the connection of the intermediate group of flues with the off-gas ducts or with the air and fuel supply ducts respectively.

5. An oven having a gasifying chamber and a heating wall therefor, said wall con-

tinuing a series of heating flues arranged in three groups, a conveying channel connecting like ends of all the flues of said series, 35 ducts for supplying fuel and air to the other ends of the flues of one end group and the intermediate group, off-gas ducts connected with the flues of the intermediate group and of the other end group at the ends distant from said conveying channel, and devices for controlling the connection of the intermediate group of flues with the off-gas ducts or with the air and fuel supply ducts respectively.

6. An oven having a gasifying chamber and a heating wall therefor, said wall containing a series of heating flues, a conveying channel connected with all the flues of said series, ducts for supplying fuel and air, 50 off-gas ducts, some of said flues being connected only with said supply ducts, others only with said off-gas ducts, and still other flues being connected with ducts of both kinds, and devices for controlling the connection of the last-named flues with the off-gas ducts or with the supply ducts respectively.

In testimony whereof, I have hereunto signed my name in the presence of two subscribing witnesses.

ARTHUR GOHMANN.
